METHOD OF RINSING HAIR WITH HYDRAZINIUM CHLORIDES

Luther O. Young and William E. Waxter, Baltimore, Md., assignors to W. R. Grace & Co., New York, N.Y., a corporation of Connecticut
No Drawing. Filed Feb. 13, 1961, Ser. No. 88,669
5 Claims. (Cl. 167—87)

This invention relates to improved hair rinse compositions and more particularly to a hair rinse containing certain hydrazinium compounds.

Hair rinses have been used for several years. Both vinegar and lemon juice have been used to remove the lime soap after shampooing the hair. Even before the advent of the earlier detergents and the cold wave compositions, improvements have been made to give added impetus to the field of hair rinses. Various types of solutions including polybasic hydroxy-acids are widely used. Solutions of citric and tartaric acid and later those of maleic acid were suggested as rinses. These materials were used as liquids but were generally sold as powders in which the customer dissolved the liquids or the correct amount of powder in water to make up the composition for use as a hair rinse.

The modern rinses, other than the color rinses, are of an entirely different nature than the earlier acid type rinses. They may be defined as film formers under proper conditions. The novel hydrazinium compounds of our composition fall within this type of composition. These compounds form what might be called monomolecular film on the hair. This type of film not only gives a pleasant sheen and appearance to the hair but also makes for easier combing and greater manageability. The hydrazinium compounds of our novel hair rinse composition form compounds with the ionic and non-ionic detergents. For this reason, the application of our novel compound is normally as a separate rinse after the shampooing of the hair has been completed. Alternately these materials may be applied with the shampoos. However, we prefer to use our formulations as a separate rinse.

The hydrazinium compounds of our composition are represented by the general formula

The R groups may be hydrogen, alkyl or substituted alkyl groups containing 1 to 45 carbon atoms. The X groups may be chlorine, bromine or iodine. The compounds have structures as shown and are named hydrazinium according to the International Union of Chemistry rules of nomenclature.

We prefer to use compounds wherein at least one of R groups contains more than eight carbon atoms. Examples of suitable compounds include: N,N-bis (hydro "tallow") N-methyl hydrazinium chloride, N,N-dimethyl-N—"coco" hydrazinium chloride, N,N-dimethyl-N-octadecylhydrazinium chloride, N,N-dimethyl-N- (hydro "tallow") hydrazinium chloride, N (2-hydroxyethyl) N,N-bis (2-stearoyloxyethyl) hydrazinium chloride, etc.

The hydrazinium compounds are present as 2 to 15 percent, preferably 3 to 5 percent of the formulation.

2

Although clear solutions of our novel hydrazinium compounds may be used, these formulations are normally made up as emulsions or dispersions. This gives the product a creamed appearance, and thus, the name creme rinse. Typical formulations of our novel hair rinse composition is as follows:

EXAMPLE I

	Acid stabilized, percent
10	Hydrazinium compound [N,N-bis (hydro "tallow") N-methyl hydrazinium chloride] 3
	Glyceryl monostearate 3
	Distilled water 94
	Water soluble perfume q.s.
15	D and C Red No. 19 q.s.

EXAMPLE II

	Hydrazinium compound [N,N-bis(hydro "tallow") N-methylhydrazinium chloride] 3
20	Glyceryl monopalmitate 3
	Distilled water 94
	Water soluble perfume q.s.

EXAMPLE III

25	Hydrazinium compound (N,N-dimethyl-N—"soya" hydrazinium chloride) 3
	Distilled water 94
	Water soluble perfume q.s.

EXAMPLE IV

30	Hydrazinium compound (N,N-bis ("coco")-N-methylhydrazinium chloride) 3
	Glyceryl monostearate 3
	Distilled water 94
35	Water soluble perfume q.s.

EXAMPLE V

40	Hydrazinium compound [N,N-bis(hydro "tallow") N-methylhydrazinium chloride] 15
	Distilled water 85
	Water soluble perfume q.s.

EXAMPLE VI

45 The novel hydrazinium compounds of our invention were evaluated as hair conditioners using the compound N,N-bis(hydro "tallow") N-methylhydrazinium chloride, hereafter referred to as CA-100. In order to evaluate these compositions in the most severe conditions a series of swatches of hair were subjected to various conditions which would develop problem hair situations. The swatches were soaked for two or three hours in 6% hydrogen peroxide. After the bleach treatment, the hair was washed with dishwashing detergent, soaked in vinegar, rinsed with water and then with the commercial 50 "creme rinses" or our CA-100 formulation. All the swatches were wound up on permanent wave curlers and oven dried at a temperature of about 200° F. As a result of the bleaching and other preliminary treatment, the hair showed very definite evidences of damage. The hair was rough and tangled very badly to the point that several strands of the hair broke when combing was attempted. The damaged hair magnified the results of hair rinse treatment. The results of this run are shown below:

3
Table I

Sample No.	Treatment	Wet combing (not curled)	Dry combing (curled)
1.....	None.....	Impossible.....	Harsh, stiff, nearly impossible.
2.....	Commercial Hair Rinse A.	Combed Easily....	Not much improvement over 1.
3.....	Commercial Softening Agent.	Hard to Comb....	Some improvement over 2.
4.....	CA-100 1% rinsed with H ₂ O.	Improved Combing.	Best combing sample, least breaking.
5.....	CA-100 1% not rinsed.....		Not as good as 4.
6.....	Commercial hair rinse B.	Combed easily....	Impossible.

The more these samples were handled and combed, the more hair broke out of each swatch. The worse the sample, the more breakage occurred. The superiority of (4) (CA-100) formulation was demonstrable throughout.

Obviously many modifications and variations of the invention as here and above set forth may be made without departing from the essence and scope thereof and only such limitations should be applied as are indicated in the appended claims.

What is claimed is:

1. The method of rinsing hair which comprises treating said hair with a 1-15% aqueous solution of a hydrazinium compound selected from the group consisting

4
of N,N-bis (hydro "tallow") N-methyl-hydrazinium chloride; N,N-dimethyl-N-“coco” hydrazinium chloride; N,N-dimethyl-N-octadecyl hydrazinium chloride; and N(2-hydroxyethyl) N,N-bis (2-stearoyloxyethyl) hydrazinium chloride.

5 2. The method of rinsing hair which comprises treating said hair with a 3-5% aqueous solution of N,N-bis (hydro "tallow") N-methyl-hydrazinium chloride.

3. The method of rinsing hair which comprises treating said hair with a 3-5% aqueous solution of N,N-dimethyl-N-“coco” hydrazinium chloride.

4. The method of rinsing hair which comprises treating said hair with a 3-5% aqueous solution of N,N-dimethyl-N-octadecyl hydrazinium chloride.

5. The method of rinsing hair which comprises treating said hair with a 3-5% aqueous solution of N(2-hydroxyethyl) N,N-bis (2-stearoyloxyethyl) hydrazinium chloride.
